US00D622151S

(12) **United States Design Patent**
Toh et al.

(10) **Patent No.:** **US D622,151 S**
(45) **Date of Patent:** **** Aug. 24, 2010**

(54) **CONTAINER**

(75) Inventors: **Kiat Cheong Toh**, Forest Hills, NY (US); **Jennifer Giannotti Genes**, Bayport, NY (US); **Alberto Mantilla**, Rego Park, NY (US); **Marisol Rodriguez**, Brooklyn, NY (US); **Anthony J. Baxter**, Hoboken, NJ (US)

(73) Assignee: **Colgate-Palmolive Company**, New York, NY (US)

(**) Term: **14 Years**

(21) Appl. No.: **29/320,257**

(22) Filed: **Jun. 24, 2008**

(51) LOC (9) Cl. **09-01**

(52) U.S. Cl. **D9/529**

(58) Field of Classification Search D9/434, D9/435, 447-449, 454, 516, 521-523, 525, D9/529, 530, 537, 539, 542, 543, 571-575; 215/381-385; 220/669

See application file for complete search history.

(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the bottom of the container is for illustrative purposes only and forms no part of the claimed design.

1 Claim, 6 Drawing Sheets
